UNITED STATES PATENT OFFICE.

WILLIAM A. LORENZ, OF HARTFORD, CONNECTICUT, ASSIGNOR, BY MESNE ASSIGNMENTS, TO THE NOISELESS TYPEWRITER COMPANY, OF MIDDLETOWN, CONNECTICUT, A CORPORATION OF CONNECTICUT.

TYPE-WRITING MACHINE.

1,164,945.

Specification of Letters Patent. Patented Dec. 21, 1915.

Application filed April 16, 1909. Serial No. 490,211.

To all whom it may concern:

Be it known that I, WILLIAM A. LORENZ, a citizen of the United States, residing at Hartford, in the county of Hartford and 5 State of Connecticut, have invented certain new and useful Improvements in Type-Writing Machines, of which the following is a full, clear, and exact description, such as will enable others skilled in the art to which 10 it appertains to make and use the same.

This invention relates to typewriting machines, and one of the objects thereof is to provide new and improved means for adjusting the platen with respect to the printing 15 plane.

Another object is to provide, in a machine employing silently operating type bars which have limited movements in the direction of the platen, means whereby the platen may 20 be moved to the proper position to receive the printing pressure of the type bars when the printing is to be effected upon a plurality of impression sheets.

Another object is to provide means for 25 holding the platen in fixed position after adjustment.

A further object is to provide a new and improved gage for measuring the thickness or thicknesses of a sheet or sheets of 30 paper upon which printing is to be effected.

Other objects will be in part obvious and in part pointed out hereinafter.

The invention accordingly consists in the features of construction, combinations of 35 elements and arrangement of parts which will be exemplified in the construction hereinafter set forth, and the scope of the application of which will be indicated in the following claims.

40 In the accompanying drawings, wherein is illustrated one of several possible embodiments of my invention, Figure 1 is a plan view of a portion of a carriage of a type writing machine sufficient to illustrate the present invention; Fig. 2 is a side view of Fig. 1, partly in section; Fig. 3 is a sectional view taken on line 3—3, Fig. 1; Fig. 4 is a front elevation of the lefthand end of the carriage shown in Fig. 1; Fig. 5 is a sectional view taken through a typewriting

machine, showing the carriage in position, and one of the type actions; Fig. 6 is a sectional view, on an enlarged scale, of the printing platen, the view being taken on line 6—6, Fig. 1; and Fig. 7 is a similar view of 55 a different embodiment of printing platen.

Similar reference characters refer to similar parts throughout the several views of the drawings.

Referring now to the drawings, 1 represents a portion of the framing of the machine supporting the bed or top plate 2 which, in turn, supports the type bars 3 and across which they are projected. The type-bars are guided to the impression 60 point by means of a cap-plate 4 and guide pins 5 and 6 and are connected by means of links 7 with a toggle cam 8, pivoted at 10 in an adjustable block 11, the latter being supported upon a ledge 12 formed upon the 65 framing of the machine. Clamp-screws, such as shown at 13, fasten the blocks 11 in position after adjustment, which may be effected by means of the adjusting screws 14. The cams 8 are oscillated to project the type-bars to impression by means of levers 15 and links 16 which connect them with the key levers, one of which is shown at 17 pivoted upon a support 18. The above-described 70 actuating mechanism for the type-bars is 75 of the general character of that illustrated in the patent to W. P. Kidder, No. 567,241, September 8, 1896, and the construction thereof is such that each type-bar has a predetermined throw in the direction of the 80 platen, the faces of the several types assuming a common plane at the termination of the thrust of said type-bars.

The carriage is constituted by two side pieces 20 and 21 connected by ball-rails 22 and 23 and a trough 24 which has a rearward extension 25. To this rearward extension is secured an angle plate 26 which slides in a sliding block 27 which block rests against the vertical face 28 of an abutment 95 30. This abutment extends upward from the framing of the machine and furnishes a rigid backing for the platen carriage, preventing recession thereof under the pressures exerted by the type-bars during printing. 100

The carriage is supported upon balls running in the grooved rail 31 supported upon oscillating arms 32 which are constructed to move the rail vertically in a substantially straight line by means of a pair of rods, one of which is shown at 33. These rods are in turn connected with the platen-shift mechanism, not shown. The carriage, therefore, may be shifted vertically for different case printing and during this operation block 27 slides up and down upon the vertical face 28 of abutment 30, and the carriage, when letter spacing movements are effected, slides in the block 27, which is held against lateral movement.

The printing platen 34 is attached at its ends to slides 35 and 36 which are dovetailed in the side pieces 20 and 21 of the carriage, this dovetailed construction being shown at 37 in Fig. 4. A platen-roll 38 has its shaft 40 journaled in slides 35 and 36 and the platen has a concave back which rests against the platen-roll. Links 41 and 42 engage the shaft 40 of the platen-roll, one on each end, and by means of studs 43 engage cam slots 44 in the side pieces 20 and 21 of the carriage. These studs are engaged by forked arms 45 attached to an oscillating or rock-shaft 46 extending across the carriage and journaled in the side pieces thereof. To the outer ends of shaft 46 are secured indicator hands 47, the outer ends of which are provided with indicators 48 which cooperate with curved, graduated indices 50 formed upon the carriage.

The operation of this structure may now be understood. Normally the platen lies in proximity to the plane assumed by the faces of the several types when they are projected to impression, so that said type-faces will just barely contact therewith. So located, the platen is in proper position to permit the printing to be effected upon a single sheet of paper positioned thereon. When it is desired to adjust the platen to or from the zero position of the faces of the type-bars the operator inserts the desired amount of paper in the carriage and in front of the printing platen 34. Then the pointers 48 are shifted to the number which corresponds to the number of sheets inserted in the carriage. This, of course, assumes that the graduation has been made in conformity with a standard thickness of paper so that each number on the scale will correspond to the number of sheets inserted in the carriage. By moving the pointer to the corresponding figure on the scale, the rock-shaft 46 and arms 45 will be oscillated, carrying the studs 43 and links 41 upward, the studs following the curvature of the cam grooves 44, thereby drawing the two slides 35 and 36, the platen roll and the printing platen 34 backward to the desired extent. The distance of the printing platen from the faces

of the types will then be that desired for printing upon the particular number of sheets inserted.

The cam-grooves 44, being disposed at a slight angle to the direction of movement of the platen and associated parts, will prevent recession of said parts during the printing operation.

I have also provided paper gaging devices on the carriage, which may be located at one side of the carriage or at both sides thereof, as shown in the drawing. These devices being similar one only need be described in order to impart a clear understanding of this feature of the invention. This gage 80 comprises fingers or jaws 51 and 52, one of which is mounted upon the slide 35 and the other upon the carriage proper. These jaws are provided with opposed faces 53 and 54 between which the paper to be measured 85 may be inserted. In Figs. 1, 2 and 3 of the drawings, the gaging faces 53 and 54 are shown in contact or closed, and when in this position the indicator-hand 47 will also be in the zero position, as will be the printing 90 platen 34. In using this device, the desired number of sheets are placed between the gaging faces 53 and 54 which have been separated by first pushing back the indicator-hand 47. The faces are then closed upon 95 the paper until the face 53 just gages the thickness of the paper. The paper is then slipped from between the jaws and inserted in the carriage, as shown at 55—Fig. 5. The distance to which the platen has been moved 100 back from the position shown in Fig. 2 will then be the correct one for printing, leaving a space between the type-faces and said platen which will cause the proper impression upon the several sheets of paper to be 105 produced.

Referring now particularly to Fig. 6 of the drawings, the platen 34 is provided with a plurality of recesses 56 leaving narrow bearing surfaces 57 which rest against the 110 platen-roll 38. The platen-roll being constructed of relatively hard material, preferably hardened rubber, it is desirable to form these recesses in the platen in order that the latter may give way or be pressed back 115 slightly in order to cushion the blow of the printing operation, thus slightly reducing the noise.

In Fig. 7 a modified form of printing platen is shown in which the platen is provided with a flat front face 58, the platen being made very thin and bearing against the platen-roll 38 at its middle portion 60, and at the edges 61 and 62, leaving recesses 63 and 64 between the platen and the platen-roll. This platen will, therefore, have three supporting surfaces against the platen-roll during the printing operation and will give way slightly, thus operating to cushion the blow and reduce the noise.

It will accordingly be seen that I have provided mechanism of the above type adapted to attain, among others, all the ends and objects above pointed out in a simple yet efficient manner and which may be manipulated with facility by the operator. Adjustment of the platen can be easily and quickly accomplished, and the indicator operates to inform the operator of its relative position with respect to the normal printing plane. The gage also furnishes a convenient method of determining upon the proper adjustment which is to be given the platen with respect to the normal printing plane.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

Having described my invention, what I claim as new and desire to secure by Letters Patent is:

1. In a typewriting machine, in combination, a pressure operated type bar, a fixed abutment on the frame of the machine in line with the movement of the type bar at substantially the end of its stroke adapted to take up the thrust thereof, a paper carrier movable relatively to said abutment, and means associated with said carrier for moving a portion thereof toward and from said abutment relatively to the normal printing plane.

2. In a typewriting machine, in combination, a plurality of type bars having a limited path of travel to a normal printing plane, a fixed abutment, a carriage adjacent said abutment and held against rearward movement thereby in the direction of movement of said type bars, and a paper carrier mounted on said carriage and movable relatively to said abutment and the normal printing plane.

3. In a typewriting machine, in combination, a plurality of type bars having a limited path of travel, a fixed abutment, a carriage adjacent said abutment, a frame mounted on said carriage, a paper roller carried by said frame and movable relatively to said frame and said abutment toward and from a normal printing plane, and means for indicating the distance between said paper roller and normal printing plane.

4. In a typewriting machine, in combination, a plurality of type bars traveling toward a normal printing plane, a fixed abutment, a carriage adjacent said abutment, a paper roller mounted on said carriage, and a flat platen adjacent said roller, said platen and platen roller being movable

on said carriage relatively to said abutment and toward and from the normal printing plane.

5. In a typewriting machine, the combination with the type bars each of which has a limited throw in the direction of the platen, of a platen carriage, an abutment which furnishes a rigid backing therefor and prevents the yielding thereof during printing, a platen roll, means on the carriage for adjusting said platen roll toward or from the end of the throw of said type bars, and means for indicating the position thereof with respect to the normal printing plane.

6. In a typewriting machine, the combination with a plurality of direct-thrust type bars each of which has a limited throw in the direction of the platen, of a platen carriage, a member forming a rigid backing for the platen carriage and preventing recession thereof during printing, a platen roll carried by the platen carriage, a platen carried thereby, an adjustable support upon the platen carriage for said roll and platen, and means for moving said support forwardly or rearwardly, whereby the platen and platen-roll may be correspondingly moved with respect to the normal printing plane.

7. In a typewriting machine, the combination with a plurality of type bars, of a platen carriage, a member forming a rigid backing for the platen carriage and preventing recession thereof during printing, a platen roll carried by the platen carriage, a platen also carried thereby, an adjustable support upon the platen carriage for said roll and said platen, means for moving said support forwardly or rearwardly, whereby the platen and platen-roll may be correspondingly moved with respect to the normal printing plane, and means for indicating the amount of such movement.

8. In a typewriting machine, in combination, a type bar adapted to have a limited throw in the direction of the platen, a platen carriage comprising a frame, a platen roller, a platen roller support adjustably mounted upon the frame, and means upon the frame adapted to move the platen roller support toward and from the end of the path of travel of the type carrier whereby the position of the platen roller with respect to the normal printing plane may be varied.

9. In a typewriting machine, the combination with a plurality of type bars, a platen carriage, a platen carrier mounted to slide upon the platen carriage, a platen and a platen-roll carried by said carrier, means for sliding said platen carrier forwardly or rearwardly upon the platen carriage, and means for actuating said last-mentioned means and for indicating the amount of movement given said platen carrier.

10. In a typewriting machine, the combination with type bars, of a platen carriage, slides mounted upon the carriage, a platen-roll journaled in said slides, a platen bearing against the platen-roll, and means for moving said slides forward and backward whereby the platen is correspondingly moved with respect to the normal printing plane.
11. In a typewriting machine, the combination with type bars which have predetermined throws in the direction of the platen, of a platen carriage, slides mounted upon the carriage, a platen-roll journaled in said slides, a platen bearing against the platen-roll, means for moving said slides forward and backward whereby the platen is correspondingly moved with respect to the normal printing plane, means for actuating said means, and indicating means co-operating with said actuating means.
12. In a typewriting machine, the combination with the type bars each of which has a predetermined throw in the direction of the platen, of a rigid abutment, a platen carriage interposed between the faces of the types and said abutment, said platen carriage being capable of movement with respect to said abutment for different case printing or letter-spacing, slides mounted upon the platen carriage, a platen-roll journaled in said slides, a platen fixed to said slides and resting against the face of the platen-roll, cam means carried by the carriage and co-operating with said slides to move them forwardly or rearwardly, whereby the platen is correspondingly moved with respect to the common plane assumed by the faces of the types when they are projected to impression, and means mounted upon the carriage for actuating said cam means.
13. In a typewriting machine, the combination with the type bars, of an abutment, a carriage resting against said abutment and movable with respect thereto for letter-spacing and different case printing, a platen frame mounted to slide upon the carriage, a platen-roll journaled therein, a platen fixed to said slide and resting against the platen-roll, a rock-shaft journaled on the carriage, said carriage having cam slots formed in the end walls thereof, arms connected with the platen-roll and having means engaging said cam-slots, an arm mounted upon each end of said rock-shaft and operatively connected with one of said first-mentioned arms, a second arm attached to said rock-shaft and adapted to rotate the same, whereby the platen frame, through said cam slots, will be moved with respect to the printing plane, and a scale with which said last-mentioned arm co-operates to indicate the position of the platen with respect to the normal printing plane.
14. In a typewriting machine, the combination with the carriage, a platen frame adjustably mounted thereon, and a paper gage one portion of which is carried by the carriage and the other by the platen frame.
15. In a typewriting machine, in combination, a carriage, a platen carrier adjustably mounted thereon, and a paper gage comprising a pair of jaws one of which is mounted upon the carriage and the other thereof upon the platen carrier.
16. In a typewriting machine, in combination, a carriage, a platen carrier mounted thereon and adapted to be adjusted to carry the platen toward or from the normal printing plane, a paper gage comprising a pair of clamp jaws one of which is mounted upon the carriage and the other thereof upon the platen carrier, and means for indicating the relative position of said jaws.
17. In a typewriting machine, in combination, a carriage, a platen carrier mounted thereon and adjustable forwardly and rearwardly to carry the platen toward or from the normal printing plane, a paper gage comprising a member carried by the platen frame, a member carried by the platen carrier, said member having opposing faces between which the paper is received.
18. In a typewriting machine, in combination, a carriage, a platen carrier adjustably mounted thereon, a paper gage comprising a pair of opposed jaws one of which is mounted upon the carriage and the other thereof upon the platen carrier, and means for indicating the relative position of said jaws.
19. In a typewriting machine, in combination, a carriage, a platen carrier adjustably mounted thereon, a paper gage comprising a pair of opposed jaws one of which is mounted upon the carriage and the other thereof upon the platen carrier, means for moving said jaws relatively to each other, and means for indicating the amount of such movement.
20. In a typewriting machine, in combination, a carriage, a platen carrier adjustably mounted thereon, a paper gage comprising a pair of opposed jaws one of which is mounted upon the carriage and the other thereof upon the platen carrier, means for moving said jaws toward each other to clamp the paper, and a scale co-operating with said moving means to indicate the relative position of said jaws.
21. In a typewriting machine, the combination with the paper roll, of a platen having a plane face for receiving the types and a curved rear face lying in contact with the paper roll, said platen having a plurality of longitudinally extending recesses upon its rear face.
22. In a typewriting machine, the combination with the platen frame, of a paper roll carried thereby, a platen having its ends

secured to the platen frame and its rear face resting in contact with the paper roll and conforming thereto, said platen being provided with a plurality of recesses upon its rear face leaving a plurality of raised portions engaging the paper roll.

23. In a typewriting machine, in combination, a movable paper carrier, a relatively fixed part, and a paper gage, one portion of

which is carried by said paper carrier and 10 the other part by said relatively fixed part.

In testimony whereof I affix my signature, in the presence of two witnesses.

WILLIAM A. LORENZ.
